CLAIM

The ornamental design for an inverter external connection box with connecting ports as shown and described.

DESCRIPTION

1. Inverter external connection box with connecting ports

1.1 is a front, right, bottom perspective view of an inverter external connection box with connecting ports according to the present application;

1.2 is a front, left, top perspective view thereof;

1.3 is a front view thereof;

1.4 is a rear view thereof;

1.5 is a left side view thereof;

1.6 is a right side view thereof;

1.7 is a top view thereof; and

1.8 is a bottom view thereof.

The broken lines in the drawings depict portions of the inverter external connection box with connecting ports that form no part of the claimed design.
